UNITED STATES PATENT OFFICE.

FRANK G. GIES, OF DETROIT, MICHIGAN, ASSIGNOR OF ONE-HALF TO TREVOR G. MURTON, OF DETROIT, MICHIGAN.

TRUCK-BODY HOIST.

Application filed March 2, 1922. Serial No. 540,606.

To all whom it may concern:

Be it known that I, FRANK G. GIES, a citizen of the United States, and residing at Detroit, in the county of Wayne and State 5 of Michigan, have invented a new and Improved Truck-Body Hoist, of which the following is a specification.

This invention relates to means for raising the front ends of the "dump" bodies of 10 vehicles, particularly the bodies of motor trucks, and its object is to provide a simple and reliable device of this character which may be controlled within narrow limits, which can be constructed at moderate cost, 15 and which will not be liable to get out of order.

This invention consists, in combination with the frame of the truck and the body therefor mounted on pivots supported on 20 the rear end of the frame, of a tubular guide pivotally mounted on the frame at the front end of the body to swing in the longitudinal vertical plane of the frame, a rope drum mounted co-axially with said 25 guide, a rope sheave at the upper end of the tubular guide, a ram slideable in the guide, a rope extending from the ram over the pulley to the drum, means to connect the ram to the body, and reversible driving 30 mechanism for the drum.

It also consists in a rope sheave mounted at the upper end of the ram and a second rope extending from the body over said 35 second sheave to the drum whereby the movement of the body relative to the ram is multiplied.

It also consists in a slideable clutch adapted to connect a driving shaft to either one of the two drum-actuating gears, a screw 40 connected to the clutch, a nut on the screw, and a guide for the nut with limiting stops so as to cause longitudinal movements of the clutch to disengage the gears when the body has reached the limits of its movements.

It also consists in guide bars connected to the body, to the tubular guide and to the ram and a cross head slideable on these rods whereby the hoist and body will always be held in proper relation to each other.

It further consists in the details of construction illustrated in the accompanying

drawings and particularly pointed out in the claims.

In the drawings, Fig. 1 is a side elevation of a portion of a truck equipped with this improved hoist. Fig. 2 is a similar elevation of the hoist on a larger scale, some of the parts being broken away 60 to show the interior. Fig. 3 is a front elevation of the lower end of the hoist. Fig. 4 is a vertical longitudinal section of the driving mechanism. Fig. 5 is a section on the line 5—5 of Fig. 2. Fig. 6 is a section 65 on the line 6—6 of Fig. 3. Fig. 7 is a side elevation of a modified form of hoist. Figs. 8 and 9 are sections on the lines 8—8 and 9—9 of Fig. 7 respectively. Fig. 10 is a section on the line 10—10 of Fig. 8. Fig. 11 70 is a plan of a vehicle chassis with this improved hoist mounted on the rear end thereof. Fig. 12 is side elevation thereof. Fig. 13 is a plan of the upper end of the hoist. Fig. 14 is a detail of a driving shaft. Fig. 75 15 is a section on the line 15—15 of Fig. 11.

Similar reference characters refer to like parts throughout the several views.

In Fig. 1 the side beams 1 of the frame of the truck support the pivots 2 on which the dumping body 3 is mounted. The hoist is mounted on the cross bar 4 of the frame and is driven by the shaft 5 which may be connected to any desired source of power and driven thereby to turn in one direction. 85 Mounted on the bar 4 are two brackets 6 and 7 which support a shaft 8 on which the worm wheel 9 is mounted. On the bracket 7 is a shell 10 which encloses the worm wheel and connected to this bracket is a frame 11 having a horizontal extension 12, as shown in Fig. 4. The shaft 5 is journaled in the extension 12 and carries a bevel pinion 14 which meshes with the bevel gears 15 and 16 which are journaled in this frame 90 11. Journaled in the hubs of these gears and in this frame is a vertical hollow shaft 17 which has slots 18 through which the pin 19 extends, which pin is mounted on a vertical stem 20 slideable in this hollow shaft.

On the hollow shaft is secured the worm 22 and slideable thereon is a clutch member 23 carrying the pins 24 adapted to enter holes 25 in one or the other bevel gear. A tubular guide 26 extends up from this frame and within it is a nut 27 on the

threaded upper end 28 of this stem 20. A handle 29 extends through the slot 30 in this guide. Thrust bearings 31 may be provided at the ends of the worm.

5 The handle 29 may be moved up or down to engage the clutch with the gear 15 or the gear 16 and thus cause the shaft 17 to turn in either direction. This will cause the nut 27 to move up or down. When the nut 10 reaches either end of the guide, it stops, and the stem is forced in the opposite direction, causing the clutch to disengage and the shaft 8 to stop. It can be caused to turn in the opposite direction by moving the 15 handle toward the opposite end of the slot 30.

Secured to this shaft 8 between the brackets 6 and 7 is a rope drum 32 and mounted on these brackets and entirely enclosing the drum is a cylindrical lower end 33 of the support 34 for the tubular guide 35 of the tubular ram 36. The brackets are formed with circular flanges 37 to receive this cylindrical end 33. The guide 25 35 has a cap 38 which carries a pin 39 on which the rope sheave 40 is mounted. A rope 41 extends from a plug 42 in the lower portion of the ram over the sheave 40 and to the drum 32. As the ram is intended to 30 slide up and down, it is provided with a longitudinal slot 43 to permit the passage of the sheave 39.

A head 44 on this ram carries a pin 45 for the sheave 46. A bracket 47 on the body 3 receives one end of the rope 48 which passes over this sheave 46 and down through the ram and support 34 to the drum 32.

Brackets 50 and 51 on the body support a pair of guide bars 52. A bracket 53 on the head 44 of the ram supports a guide bar 54 which is slideable in the bracket 55 on the tubular guide 35. A cross head shown in Fig. 5 consists of a central collar 56 and two side arms 57 which receive the trunnions 58 on the collars 59. The central collar is slideable on the guide bar 54 and the collars 59 are slideable on the bars 52.

When the shaft 8 and drum 32 are rotated to wind the ropes 41 and 48, each unit of 50 circumferential movement of the drum at the centers of the ropes will cause the ram to rise one unit because of the rope 41 and the lower corner of the body 3 to rise two units because of the rise of the sheave 46 55 and rise another unit because of the winding of the rope 48. The bracket 47 will therefore rise three times as fast as the sheave 46.

As the guide bars 52 slide up in the collars 59, the angle between these bars 52 and bar 54 will change, but the distance between the adjacent end of the body 3 and the bracket 55 on the hoist will remain nearly constant so that the rope 48 will be 65 nearly parallel to the axis of the ram at all

times. The ropes 41 and 48 may be of wire or fibre as may be preferred.

Because of the worm 22 and worm wheel 9, the clutch 23 may be disengaged at any position of the body 3 without danger of 70 the body changing its position, the worm and worm gear acting as a lock on the drum.

In Figs. 7 to 10 is shown a hoist adapted for light trucks. These figures also disclose a truck body 60 having front extensions 61 75 which project beyond the hoist, the body being formed with a recess 62 to receive the hoist. The side bars 1 and cross bar 4 of the frame of the vehicle are the same as above described and on the bar 4 are mounted the brackets 6 and 7 which support the shaft 63 for the drum 64. This shaft is shown with a crank handle 65 at one end and its middle portion is eccentric to its journals so that the drum 64 will be revolved 85 with its teeth 66 meshing with the internal teeth 67 formed on the flange 68 of the bracket 7. The cylindrical lower end 33 of the support 34 of the tubular guide 35 is again mounted on the flanges 37 and 68 as 90 above described.

The brackets 69 which support the upper ends of the guide rods 52 are fitted to the curved wall of the recess 62 but otherwise this hoist is substantially the same as that above described and the same reference characters are employed to designate the same parts.

When the crank handle 65 is turned in 100 either direction, the drum 64 rotates slowly in the opposite direction, and because of this great gain in power it is an easy matter for a workman using a twenty inch crank handle to dump a body having a fifteen hundred pound over-balance at its front end, which over-balance is seldom exceeded in the lighter trucks. In heavy trucks, the mechanical drive is to be preferred, although the differential gearing shown in Fig. 10 105 can be so proportioned that one man can dump very heavy loads with the usual over-balance.

Instead of using this hoist to elevate the front ends of vehicle bodies to dump them, 115 it may be advantageously mounted on the rear ends of the chassis, with or without a body, the chassis being provided with a transverse track 70 on which a base 71 is slideable. The sides 7 of this base are similar to those shown in the previously described constructions, and, as in Figs. 7 to 10 inclusive, the shaft 63 may be turned by a crank handle.

In this construction the tubular guide 35 125 and the ram are the same as above described, as are also the head 44 and sheave 46, but the guide 54 is omitted as the reason for it is lacking. A yoke 73 may be mounted on the pin 39 and may have ears 74 to which 130

the guy cables 75 may connect, these cables connecting to eye-bolts 76 at the forward portion of the chassis 80. A pin 77 may be used to hold the hoist at the desired point 5 on the track 70.

The shaft 63 may have a block 78 on its outer end and a fork 79 on the handle shaft 81 may be pivoted thereto by a bolt 82. The handle 83 may therefore be swung up 10 against the hoist when that is swung down, as shown in dotted lines in Figs. 11 and 12, and slid over to one side of the chassis. This construction is especially adapted for use by building contractors and for use on 15 trucks employed to handle wrecked automobiles, as it supplies a powerful and convenient hoist which can be swung down and moved over to one side so as not to obstruct the loading of the truck and which when 20 swung down leaves the truck body available for other purposes.

The details of construction and the proportions of the parts may all be changed by those skilled in the art without departing 25 from the spirit of my invention as set forth in the following claims.

I claim:-

1. In a hoist, the combination of a horizontal shaft and a rope drum mounted 30 thereon, a guide pivoted on said shaft, a ram slideable in the guide, a rope sheave at the upper end of the guide, a rope extending from the lower end of the ram over the sheave to the drum, a sheave at the upper 35 end of the ram, and a rope extending from the body over the second sheave to the same drum.

2. In a hoist, the combination of a horizontal shaft and a rope drum mounted 40 thereon, a guide pivoted on said shaft, a ram slideable in the guide, a rope sheave at the upper end of the guide, a rope extending from the lower end of the ram over the sheave to the drum, a sheave at the upper 45 end of the ram, a rope extending from the body over the second sheave to the drum, and means to drive the drum in either direction.

3. In a hoist, the combination of a horizontal shaft and a rope drum mounted 50 thereon, a guide pivoted on said shaft, a ram slideable in the guide, a rope sheave at the upper end of the guide, a rope extending from the lower end of the ram over the sheave to the drum, a sheave at the upper 55 end of the ram, a rope extending from the body over the second sheave to the drum, reversing gears to drive the drum in either direction, and means actuated by the reversing 60 gears to disconnect the drum therefrom when the ram has reached the limits of its upward or downward movements.

4. In a dumping hoist for vehicle bodies, the combination of a horizontal shaft and a 65 rope drum mounted thereon, a guide piv-

oted on said shaft, a ram slideable in the guide, a rope sheave at the upper end of the guide, a rope extending from the lower end of the ram over the sheave to the drum, a sheave at the upper end of the ram, a rope 70 extending from the body over the second sheave to the drum, a guide bar attached to the vehicle body, a second guide bar attached at its upper end to said ram, means connected to the guide for the ram to guide 75 the lower end of the second guide bar, and a cross head slideably mounted on said guide bars.

5. In a dumping hoist for vehicle bodies, the combination of a horizontal shaft and a 80 rope drum mounted thereon, a guide pivoted on said shaft, a ram slideable in the guide, a rope sheave at the upper end of the guide, a rope extending from the lower end of the ram over the sheave to the drum, a sheave at the upper end of the ram, a rope 85 extending from the body over the second sheave to the drum, a guide bar attached at its upper end to the ram, a bracket on the guide for the ram in which bracket said 90 guide bar is slideable, a pair of guide bars mounted on the vehicle body, and a cross head slideably mounted on said guide bars to position the hoist relative to the body.

6. In a dumping hoist for vehicle bodies, the combination of a horizontal shaft and a 95 rope drum mounted thereon, a tubular guide and a bearing for the lower end thereof, a ram slideable in the guide, a pivoted vehicle body, means connecting the ram and the drum and the body whereby the body 100 may be elevated, a guide bar attached to the body, a second guide bar attached at its upper end to said ram, means connected to the tubular guide for the ram to guide the lower 105 end of the second guide bar, and a cross head slideably mounted on said guide bars.

7. In a dumping hoist for vehicle bodies, the combination of a tubular guide and a bearing for the lower end thereof on which the guide may swing in a vertical plane 110 parallel to the line of the vehicle, a ram slideably mounted in the guide, a rope to elevate the ram in the guide and a second rope extending from the top of the ram to one end of the body whereby that end of the body may be elevated, a pair of parallel 115 guide bars mounted on the body, a third bar mounted on the ram and guided by the tubular guide, and a cross head slideably on said 120 bars to cause the hoist to swing toward the body as that is being elevated.

8. In a dumping hoist for vehicle bodies, the combination of a tubular guide and a bearing for the lower end thereof on which the guide may swing in a vertical plane 125 parallel to the line of the vehicle, a ram slideably mounted in the guide, a rope to elevate the ram in the guide and a second rope extending from the top of the ram to one end 130

of the body whereby that end of the body may be elevated, a pair of parallel guide bars mounted on the body, a third bar mounted on the ram and guided by the tubular guide, and a cross head slidable on said bars to cause the hoist to swing toward the body as that is being elevated, said cross head comprising a member slidable on the bar connected to the ram and a pair of collars pivotally connected to said slidable member and slidable on the bars connected to the body.

9. In a hoist, the combination of a base mounted on a vehicle chassis, a horizontal shaft mounted on the base, a rope drum

mounted on the shaft, a hoist pivotally mounted on said shaft and adapted to swing thereon and comprising a guide member, a ram slidable therein, rope sheaves mounted on the upper ends of the guide and ram, and a pair of ropes adapted to be wound on the drum, one of said ropes passing over each sheave, the rope passing over the sheave on the guide connecting to the lower end of the ram, a dumping body mounted on the vehicle chassis, means connecting the rope passing over the sheave on the ram to said body, and a slidable connection between the ram and body.

FRANK G. GIES.
